(57) **CLAIM**

The ornamental design for a coil, as shown and described.

DESCRIPTION

FIG. 1 is an isometric view of a coil, which embodies my design;

FIG. 2 is an isometric view of the coil;

FIG. 3 is a top plan of the coil;

FIG. 4 is a bottom plan view of the coil;

FIG. 5 is a side view of the coil;

FIG. 6 is a side view of the coil;

FIG. 7 is a side view of the coil; and,

FIG. 8 is a side view of the coil.

The broken lines depict portions of the coil that form no part of the claimed design.
